UNITED STATES PATENT OFFICE.

ROGER M. NEWBOLD, OF CHICAGO, ILLINOIS, ASSIGNOR TO THE ADAMS & WESTLAKE COMPANY, A CORPORATION OF ILLINOIS.

DESIGN FOR AN AUTOMOBILE-LAMP.

44,449.

Specification for Design.

Patented Aug. 5, 1913.

Application filed February 14, 1912. Serial No. 677,635. Term of patent 14 years.

To all whom it may concern:

Be it known that I, ROGER M. NEWBOLD, a citizen of the United States, residing at Chicago, county of Cook, and State of Illinois, have invented a new, original, and ornamental Design for an Automobile-Lamp, of which the following is a specification, reference being had to the accompanying drawing, forming a part thereof and

showing an elevation of the lamp embodying the design.

I claim—

The ornamental design for an automobile lamp, as shown.

ROGER M. NEWBOLD.
